WILLIAM JAMES HADDEN, OF GLASGOW, SCOTLAND, ASSIGNOR TO DONALDSON MANUFACTURING COMPANY LIMITED, OF GLASGOW, SCOTLAND

GOLF CLUB

Application filed August 23, 1928, Serial No. 301,672, and in Great Britain July 12, 1928.

This invention relates to metallic shafted metal headed golf clubs, that is, golf clubs comprising a metallic shaft and a metallic head.

5 The chief object of the present invention is to provide such a golf club in which the shaft and head can easily and quickly be detached, primarily for the purpose of allowing a prospective purchaser to try a number 10 of different heads and shafts together in order to select the combination most suited to his or her physique and style of play, and also for facilitating transport and storage.

Where heads and shafts are to be attached and detached often, for a satisfactory club it is desirable that:

(1) The shaft and head when secured together be rigidly and very securely joined so as to provide a club having all the characteristics 20 of those of the more usual type, in which the head and shaft are permanently secured together, and so as to withstand the impacts to which it is subjected in use.

(2) The shaft and head be easily and quickly 25 detachable.

(3) Continuous attachment and detachment of head and shaft should not damage either of these parts in any way.

Other objects of the invention are to attain 30 the desideratum set forth in (1) and (3) above.

A further object of the invention is to provide an "iron" golf club that is, a metal-headed club, having easily detachable head and shaft, and in which a metal to metal joint is provided between the head and shaft for it is well known that a wood to metal joint between head and shaft is unsatisfactory in use, particularly in a club of the 40 present type with a detachable shaft for, owing to the relative softness of wood it very soon becomes damaged or worn and the joint becomes loose.

A still further object of the invention is to provide a metallic shafted "iron" golf club, the head and shaft of which are easily and quickly separable, and which can be very securely joined together, but which will not necessitate the use of additional parts, besides the head and shaft, for securing them

together, and will therefore not spoil the balance of the head by increasing the weight at the joint.

A still further object of the invention is to provide an easily detachable and efficient joint for steel shafted "iron" golf clubs which is of a simple nature, robust, and comparatively inexpensive to manufacture.

A still further object of the invention is to provide a steel shafted "iron" golf club having an easily detachable but tightly securable head and shaft, in which the joint between head and shaft will not decrease in efficiency over a long period of use of the club, and of separation and attachment of head and shaft.

A still further object is to provide a steel shafted "iron" golf club having an easily separable but tightly securable head and shaft, which, under conditions of wear, and under mass production conditions entailing inaccuracies in manufacture, will always ensure a tight and satisfactory joint between head and shaft.

In order that the invention may be clearly understood, a practical embodiment thereof will now be described with reference to the accompanying drawing, whereon:

Fig. 1 is a sectional view of the metallic shaft for "iron" golf clubs.

Fig. 2 is a sectional view showing the shaft secured in the head, and

Figs. 3 and 4 are, respectively, elevation and plan of the club striking the ball, and illustrate the forces to which the golf club is subjected in use.

In Figs. 1 and 2 of the drawing, the numeral 1 denotes the tubular tapering metallic shaft, while numeral 2 denotes the forged steel head. As shown, the head has formed in it a socket, the outer part 3 of which is internally tapered, and the inner part 4 of which is internally screw threaded. The shaft 1 is tapered and is the counterpart of the internally tapered part 3. The taper extends up to the point marked 5, a short distance from its end, and the remainder 6 is made parallel sided or cylindrical and in the form of a screw, so as to screw into the corresponding threaded part 4 in the socket. The screw

6 is formed by suitably bending or shaping the metal by means of dies or otherwise.

When the shaft is screwed into the head, the tapering parts 1 and 3 are brought into inter-engagement, and, as the two contacting faces are of metal and are rigid, they bind frictionally very tightly together, in similar manner to that in which a glass stopper grips the neck of a glass bottle. Owing to the fact that the joint is metal to metal, the shaft and head can be joined and separated a great number of times without causing damage or impairing the joint in any way. The construction forms an exceedingly simple joint, which is very easy to join and separate, no additional parts being necessary, and therefore the delicate balance of the club at the head is unaffected, as would be the case if ferrules, plugs or sleeves were used. The use of the usual cross-pin is not even required. When it is desired to change the head or shaft, the shaft can be withdrawn readily by placing the head between the player's feet and screwing back the shaft.

It is important that the inter-engaging tapered parts of the shaft and socket should be so proportioned that they are drawn very tightly together before the screwed part is screwed to its limit into the socket, and before the lower end of the tapered part of the shaft can come against the upper end of the threaded part of the socket, and also so that these do not give or wear with use so as to be relatively variable in diameter, as would be the case with a wooden part. To ensure the interengagement of the tapered parts in this way, the diameter of the shaft is usually made just too great to permit engagement with the tapered part of the socket the entire distance from top to bottom thereof. The result is that the lower end of the shaft stops short of the lower end of the socket, and the lower end of the shaft taper stops short of the upper end of the socket screw threads when the shaft is screwed fully home. If, therefore, say, the shaft is made slightly too small, the clearances thus formed will ensure inter-engagement.

Referring now to Figs. 3 and 4, when the club strikes the ball 7 with an impact denoted by A, two forces act on the club, namely, a maximum bending movement A_y , where y is the distance from the centre of gravity of the ball to the point on the shaft which bends most, and a torsion couple A_x at a given point, where x is the horizontal distance from the centre of gravity of the ball to the given point on the shaft.

It will therefore be evident, that to get the best results out of the club, the shaft must be of material thin enough to bend and twist as required by the impact, so as to store energy, in order that, during the "follow through" of the club the shaft will give the

"kick" inherent in good golf clubs. The method of screw threading the lower end of the shaft itself in accordance with this invention therefore enables a detachable joint to be obtained without impairing the resiliency of the shaft in any way, without weakening the shaft by cutting a thread thereon, and without spoiling the balance of the club by using additional parts or by reinforcing the shaft, as for instance, by casting a sleeve thereon and threading the sleeve.

The golf club illustrated is for a right hand player, and the parts 4 and 6 have left-handed threads, so that, when the club strikes the ball or the ground, the aforesaid torsion couple tends to tighten the joint by screwing the shaft further into the head. For a left-handed player the threads would be right-handed.

It will be noted that the surface area of the inter-engaging tapered parts is considerably greater than the area of the inter-engaging threaded parts, and this proportion may even be increased over that shown, because the threaded part mainly serves to draw the tapered parts into inter-engagement and retain them there, the most important part of the joint being that at the tapered parts. The joint formed may therefore be termed a "combined screw and push joint", the "push" joint being that formed between the tapering parts of shaft and head, in the manner described.

It is to be understood that the invention is applicable to all kinds of "iron" heads fitted with metallic shafts.

I claim:—

1. A two piece golf club comprising in combination a metallic head and a tubular tapering metallic shaft which are quickly and easily detachable, or securable together with a metal to metal joint, said head having a socket with an inner cylindrical screw threaded part at the lower end thereof and an internal plain tapering part at the upper end thereof tapered to correspond with the shaft, of comparatively slight taper and merging into said screw threaded part, and said shaft having a cylindrical screw threaded part at the smaller end thereof corresponding in size to the internal threaded part on the socket, the screw being formed on the shaft by bending the metal of the shaft itself into screw formation without thickening, reinforcing, or cutting the metal, the smallest diameter of the tapering part of the shaft being slightly greater than that which allows engagement of the tapering parts of the shaft and socket over the whole length of the tapering part of the socket, said parts being proportioned to leave a clearance in the socket below the lower end of the shaft and the bottom of the socket.

2. A metal headed golf club comprising two separate elements only, namely, a metal-

- lic head, and a tubular tapering metallic shaft, which are quickly and easily detachable, or securable together with a metal to metal joint, said head comprising, a socket, 5 an inner cylindrical screw threaded portion at the lower end thereof, an internal plain tapering part at the upper end of the socket, the taper being comparatively slight and corresponding to the taper of the shaft, and 10 said tapering shaft having a cylindrical screw threaded portion at the smaller end thereof corresponding in size to the screw threaded part of the socket and formed by bending the metal of the shaft itself into screw formation, without thickening, reinforcing, or cutting the metal, the area of inter-engagement of the tapering parts being considerably greater than that of the screw-threaded parts, whereby the head and shaft 15 bind frictionally together. 5. In a two piece, metal headed golf club, 75 a tubular metallic shaft comprising a tapered portion and a cylindrical portion, said cylindrical portion terminating said shaft and adjoining the small end of said tapered portion and having screw threads impressed integrally into the metal thereof, a metallic head provided with a socket extending only part of the way through said head and said socket having an outer tapered portion whose maximum diameter is outside and having an inner cylindrical portion contiguous to the inner end of said tapered portion, the cylindrical portion of said socket being screw threaded for receiving the screw threaded portion of said shaft, and the tapering portion of said socket throughout its length corresponding in slope to the tapered portion of said shaft the threaded portion of the shaft being of such length that when the tapered portion of said shaft has penetrated the maximum distance into said socket there is 80 a clearance between the extremity of said shaft and the extremity of said socket. 6. In a two piece, metal headed golf club, 85 a tubular metallic shaft comprising a tapered portion and a cylindrical portion, said cylindrical portion terminating said shaft and adjoining the small end of said tapered portion and having screw threads impressed integrally into the metal thereof, a metallic head provided with a socket extending only part of the way through said head and said socket having an outer tapered portion whose maximum diameter is outside and having an inner cylindrical portion contiguous to the inner end of said tapered portion, the cylindrical portion of said socket being screw threaded for receiving the screw threaded portion of said shaft, and the slope of the tapering portion of said socket corresponding to the slope of the tapering portion of said shaft, the minimum diameter of the tapered portion of said shaft being slightly greater than the inner diameter of the screw threaded portion of said socket, whereby the tapered portion of said shaft can not engage the threaded portion of said socket, and the threaded portion of the shaft being of such length that the extremity of said shaft can 90 not penetrate to touch the inner extremity of said socket. 7. In a two piece metal headed golf club, 95 a tubular metallic shaft comprising a tapered portion and a cylindrical portion, said cylindrical portion terminating said shaft and ad-
- 15 20 25 30 35 40 45 50 55 60 65 70 75 80 85 90 95 100 105 110 115 120 125
- lic head, and a tubular tapering metallic shaft, which are quickly and easily detachable, or securable together with a metal to metal joint, said head comprising, a socket, 5 an inner cylindrical screw threaded portion at the lower end thereof, an internal plain tapering part at the upper end of the socket, the taper being comparatively slight and corresponding to the taper of the shaft, and 10 said tapering shaft having a cylindrical screw threaded portion at the smaller end thereof corresponding in size to the screw threaded part of the socket and formed by bending the metal of the shaft itself into screw formation, without thickening, reinforcing, or cutting the metal, the area of inter-engagement of the tapering parts being considerably greater than that of the screw-threaded parts, whereby the head and shaft 15 bind frictionally together. 5. In a two piece, metal headed golf club, 75 a tubular metallic shaft comprising a tapered portion and a cylindrical portion, said cylindrical portion terminating said shaft and adjoining the small end of said tapered portion and having screw threads impressed integrally into the metal thereof, a metallic head provided with a socket extending only part of the way through said head and said socket having an outer tapered portion whose maximum diameter is outside and having an inner cylindrical portion contiguous to the inner end of said tapered portion, the cylindrical portion of said socket being screw threaded for receiving the screw threaded portion of said shaft, and the tapering portion of said socket throughout its length corresponding in slope to the tapered portion of said shaft the threaded portion of the shaft being of such length that when the tapered portion of said shaft has penetrated the maximum distance into said socket there is 80 a clearance between the extremity of said shaft and the extremity of said socket. 6. In a two piece, metal headed golf club, 85 a tubular metallic shaft comprising a tapered portion and a cylindrical portion, said cylindrical portion terminating said shaft and adjoining the small end of said tapered portion and having screw threads impressed integrally into the metal thereof, a metallic head provided with a socket extending only part of the way through said head and said socket having an outer tapered portion whose maximum diameter is outside and having an inner cylindrical portion contiguous to the inner end of said tapered portion, the cylindrical portion of said socket being screw threaded for receiving the screw threaded portion of said shaft, and the slope of the tapering portion of said socket corresponding to the slope of the tapering portion of said shaft, the minimum diameter of the tapered portion of said shaft being slightly greater than the inner diameter of the screw threaded portion of said socket, whereby the tapered portion of said shaft can not engage the threaded portion of said socket, and the threaded portion of the shaft being of such length that the extremity of said shaft can 90 not penetrate to touch the inner extremity of said socket. 7. In a two piece metal headed golf club, 95 a tubular metallic shaft comprising a tapered portion and a cylindrical portion, said cylindrical portion terminating said shaft and ad-
- 15 20 25 30 35 40 45 50 55 60 65 70 75 80 85 90 95 100 105 110 115 120 125

joining the small end of said tapered portion and having screw threads impressed integrally into the metal thereof, a metallic head provided with a socket extending only 5 part of the way through said head and said socket having an outer tapered portion whose maximum diameter is outside and having an inner cylindrical portion contiguous to the inner end of said tapered portion, the cylindrical portion of said socket being screw threaded for receiving the screw threaded portion of said shaft, and the tapering portion of said socket throughout its length corresponding in slope to the tapered portion 10 of said shaft, the screw threaded cylindrical portion of said shaft being of such length that when the tapered portion of said shaft has penetrated the maximum distance into said socket there is a clearance between the 15 extremity of said shaft and the extremity of said socket.

8. In a two-piece, metal headed golf club, a tubular metallic shaft comprising a tapered portion and a cylindrical portion, said cylindrical portion terminating said shaft and adjoining the small end of said tapered portion and having screw threads impressed integrally into the metal thereof, a metallic head provided with a socket extending only part of 25 the way through said head and said socket having an outer tapered portion whose maximum diameter is outside and having an inner cylindrical portion contiguous to the inner end of said tapered portion, the cylindrical 30 portion of said socket being screw threaded 35

for receiving the screw threaded portion of said shaft, and the slope of the tapering portion of said socket corresponding to the slope of the tapering portion of said shaft, the minimum diameter of the tapered portion of 70 said shaft being slightly greater than the inner diameter of the screw threaded portion of said socket, whereby the tapered portion of said shaft can not engage the threaded portion of said socket, and the screw threaded cylindrical portion of said shaft being of such length that the extremity of said shaft can not penetrate to touch the inner extremity of said socket.

9. In a golf club, a shaft tapered towards 75 its lower end and terminating in a cylindrical shank formed integral with the tapered portion and having threads of no greater diameter than the lower end of the tapered portion, and a head having a neck formed 80 with a socket opening through its upper end, said socket being tapered downwardly to the same degree as the tapered portion of the shaft and having a threaded lower portion 85 of uniform diameter, said shaft having its threaded portion screwed into the threaded portion of the socket with its lower end spaced from the bottom of the socket and the tapered portion of the shaft tightly wedged 90 into the tapered portion of the socket to insure a firm wedging connection between the shaft and head.

In testimony whereof I affix my signature.

WILLIAM JAMES HADDEN. 100
